ATTORNEY.

UNITED STATES PATENT OFFICE.

ELIE W. LABOMBARDE, OF NASHUA, NEW HAMPSHIRE.

LIQUIDPROOF PAPER VESSEL.

Application filed September 2, 1921. Serial No. 497,885.

To all whom it may concern:

Be it known that I, ELIE W. LABOMBARDE, a citizen of the United States, and resident of Nashua, in the county of Hillsborough and State of New Hampshire, have invented certain new and useful Improvements in Liquidproof Paper Vessels, of which the following is a specification.

This invention relates to paper vessels or boxes to contain liquids such as milk, or partly liquid substances such as oysters and pickles, and has particular reference to vessels or boxes made from flat blanks which, when folded, have flap portions glued together in overlapping relationship.

Boxes of the general character referred to have been successfully used for holding and carrying ice cream which, being frozen, is not liable to escape until melted. Such boxes, for such substances, are usually emptied after a short period of time, and therefore it is not necessary that they shall be very durable or capable of being more or less roughly handled for any material length of time.

The object of the present invention is to provide paper receptacles which are strong enough and so liquid-proof that they can be practically used for holding, without leakage, such liquid as milk, during transportation and delivery to the consumers.

It is also an object of the invention to provide vessels of this character which do not require localized application of the waterproofing substance, such as paraffine wax, in order to be able to adhesively connect overlapping portions of the blanks.

Further objects are to provide liquid-proof paper vessels which can be sealed and will remain sealed during transportation, and which can be readily opened when desired.

With these objects in view, my invention consists in the improved box or vessel, and in the improved blank therefor, substantially as hereinafter described and claimed.

Of the accompanying drawings:

Figure 1 is a plan view of a blank cut and creased to form one of my improved receptacles.

Figures 2, 3 and 4 are perspective views illustrating how the blank is folded, portions of each view being broken out to show interior parts.

The particular form of blank illustrated

in Figure 1 comprises a bottom section 12, with flaps 13, 13, two wall sections 14, 15, one having side flaps 16 and the other having side flaps 17. The wall section 14 has an end flap 18 and extension 19 thereof, and the wall section 15 has an end flap 20. The flaps 17 have extension flaps 21.

The material of which the blank is made consists of paper board by which I mean sheet paper thick enough to contain in its interior sufficient waterproofing material, such as paraffine wax, to effectually prevent the passage of liquid such as milk, without relying upon any surface coating of the wax. Ordinary paraffined paper is quite thin, but is successfully used for wrapping purposes. Its thinness however necessitates the presence of a coating of wax on one or both surfaces. This surface coating prevents the adhesion of any well-known or ordinary glue used for securing overlapping portions of the blank or sheet. Any method employed for removing or preventing any surface coating on this thin paper would leave insufficient wax in the fibers to enable a receptacle or box to be formed therefrom and be capable of use for the transportation of milk. Therefore I employ paper board not only for its strength but also because of its thickness, if filled with wax and having no surface coating, being capable of retaining enough wax to prevent leakage.

While the paper board may be treated as presently described before the blanks are cut therefrom, I prefer to cut the blanks first and then treat them. This is because the cutting of the blanks leaves some small pieces. As there is no economical way of reclaiming pieces of paper which carry paraffine while the pieces can be used in the manufacture of cheap grades of paper if they are clear of paraffine, it is more economical in the end to cut the blanks from un-waxed paper board and then wax the blanks.

In preparing the paper board for use in making liquid-proof containers, whether said board is in the form of a web or large sheets or cut and creased blanks such as shown in Figure 1, I employ a machine having heated rolls with wax supplying means such as illustrated in Letters Patent 1,218,419, granted to me March 6, 1917. For present purposes however I employ nothing to prevent equal distribution of the

wax on the entire surface or surfaces of the paper board. Preferably I employ two sets of heated rolls between which the paper board is passed under such pressure that the 5 wax is squeezed into the interior of the board beyond or away from both surfaces thereof. It is important that both surfaces of the board shall be so free from wax that the glue used when the blank is folded will 10 adhere to either surface, because flap portions of the blank are overlapped. In other words the paraffine wax is driven away from both surfaces of the board so glue will adhere firmly to any portion thereof. At the 15 same time the character of the board material is such that it is capable of holding, below or within its surfaces, sufficient wax to enable a container made therefrom to hold liquid without leakage for such length 20 of time as will be ample to cover the period from filling, through transporation, to the user.

When the blank illustrated, and made and treated as described, is to be folded, 25 glue is first applied to certain portions thereof, as, for instance, to those surfaces of the flaps 13, 13 and 17, 17, which, when the blank reaches the form shown in Figure 2 appear uppermost in that 30 figure. Then, as the folding continues toward the form shown in Figure 3, the flaps 16, 16, pass inside the flaps 17, 17, and the flaps 13, 13, are turned up against the outside flaps 17, 17. While so folded the overlap- 35 ping flaps are held under pressure for a sufficient length of time to enable the glue to "set." In practice I nest the articles (the tops, 18, 19, 20, 21 being left open) partly to aid in holding the glue-bearing flaps in 40 contact and partly to reduce space required for storage or shipment prior to filling them.

After one of the receptacles has been filled, the flap 18 is closed as shown in Figure 3, carrying the extension 19 with it. Said flap 45 18 is so proportioned that its lateral margins will come to rest on the upper edges of the wall flaps 16, 16, thereby limiting the downward movement of said flap 18 and preventing a splashing of the milk or other liquid. Then the flap 20 is folded down between the side flaps 21, 21, this movement of the flap 20 bending the lip flap 19 backward and making a tight joint along that fold. 50 Next the side flaps 21, 21, are folded toward each other, said flaps being so proportioned that their edges substantially meet flush. This folding of the flaps 21, 21 down flat brings pressure upon the lateral margins of the flap 18 and practically clamps them 55 on the upper edges of the wall flaps 16, 16, and effects tight joints along said edges. Of course the fact that the material is comparatively thick and strong has much to do with this effecting of tight joints.

60 65 It now only remains to secure the flaps

21, 21, in their flat and clamping positions. This is effected by means of a gummed sealing strip 22 (Fig. 4) which extends across the vessel so as to cover the crevice between the edges of the flaps 21, 21, and to 70 also extend part way down the front and rear wall sections. Any kind of gummed strip can be employed without risk of the gum affecting milk because there are two complete layers of the paper board material 75 below the flaps 21, 21, viz: the flaps 18 and 20.

To open the container it is only necessary to rip the strip 22 away, which is easily effected. Then the flaps 21 and 20 can be 80 lifted to the position shown in Figure 3 which thus gives access to the lip flap 19. Said lip flap enables the user to lift the cover flap 18 as gently as may be necessary to avoid undesirable agitation of the milk 85 or cream.

In another application filed concurrently herewith, Serial No. 497,886, I have described and claimed means for making the corners of paper vessels leak-tight, by means 90 of corner patches. If desirable I may apply similar patches to the blank illustrated and described herein, since the treatment of the paper board hereinbefore explained is conducive to the easy location of the patches in 95 proper corner positions.

By the employment of the term paraffine or paraffine wax herein I do not limit myself to that specific material as the liquid-proofing substance, although I believe that 100 material to be best for the purpose.

As shown in Figures 3 and 4, the flaps 13, 13, of the bottom section 12 extend up outside of and are glued to the outer surface of the outer wall portions 17 and they are nearly 105 as wide as said portions 17. This greatly strengthens the lower part of the receptacle and does not interfere with close adherence of the portions 16 and 17. If the flaps 13, 13, were to extend between the portions 16 and 17, some areas of the latter would be held apart. And if the flaps 13, 13, were to extend up, inside the inner wall portions 16, they would prevent the interior of the receptacle from having a smooth surface. The 110 wall portions 16 and 17 are of exactly the same width so that the edges of the portions 16 extend close in to the angles where the portions 17 meet the sections 15, thereby lessening the liability of liquid passing 115 around the vertical edges of the portions 16.

Having now described my invention, I claim:

1. The method of making a liquid-proof 125 paper board vessel, consisting in coating paper board with wax, subjecting said paper board to heat and pressure to drive the wax into the fibers below both surfaces of the board and leave said surfaces in glue-hold- 130

- ing condition, and then applying glue to portions of the board and pressing them in contact with other portions thereof.
2. The method of making a liquid-proof paper board vessel, consisting in cutting a blank from paper board, applying wax to the blank and subjecting it to heat and pressure to drive the wax away from both surfaces of the blank, and folding the blank to receptacle form with glue directly between overlapping portions thereof.
3. The method of making liquid-proof vessels by folding paper board stock and gluing overlapping portions thereof together, characterized by applying wax to the stock and removing the wax from the surfaces into the interior of the stock prior to the folding and gluing.
4. A paper board blank for making a box, said blank of single thickness being interiorly impregnated with liquid-repellant material, both surfaces of the blank being in condition to enable overlapping portions thereof to be glued together.
5. A liquid receptacle comprising a single thickness of paper board cut and creased to form a bottom section, wall sections and a plurality of flaps, said board being uniformly interiorly impregnated with wax and having overlapping flaps glued together.
6. A liquid receptacle comprising a folded piece of wax-impregnated paper board having overlapping glued wall portions, a cover section proportioned to seat marginally on the upper edges of wall portions, and flaps to clamp said cover section in seated position.
7. A liquid receptacle comprising a folded piece of wax-impregnated paper board having overlapping glued wall portions, a cover section proportioned to seat marginally on the upper edges of wall portions, said cover section having a folded lip, and flaps to clamp said cover section in seated position.
8. A liquid receptacle comprising a folded piece of wax-impregnated paper board having overlapping glued wall portions, a cover section proportioned to seat marginally on wall members of the receptacle, and flaps located and proportioned to overlie the cover section to hold it in seated position.
9. A liquid receptacle comprising a folded piece of wax-impregnated paper board having overlapping glued wall portions, a cover section having a foldable lip and proportioned to seat marginally on the upper edges of wall portions, a flap foldable over the cover section and its lip, and two flaps extending from the outer wall portions and foldable over the flap which is to overlie the cover section.
10. A liquid receptacle comprising a folded piece of wax-impregnated paper board having overlapping glued wall portions, a cover section marginally bearing on the upper edges of the inner wall portions, a flap folded over the cover section, the outer wall portions having flaps folded toward each other over the flap which overlies the cover section, and a sealing strip for securing together the said flaps of the outer wall portions.
11. A liquid receptacle comprising a folded piece of wax-impregnated paper board having a bottom section and having overlapping glued wall portions, a foldable cover section, foldable flaps to overlie and hold the cover section in position, and flaps of the bottom section folded against the outer surfaces of the outer overlapping wall portions and glued thereto.

In testimony whereof I have affixed my signature.

ELIE W. LABOMBARDE.
